UNITED STATES PATENT OFFICE

92,699

DESIGN FOR A COMBINED AUTOGRAPHIC REGISTER AND CASH DRAWER

Robert Davol Budlong, Chicago, Ill., assignor to United Autographic Register Company, a corporation of Illinois

Application April 20, 1934, Serial No. 51,473

Term of patent 7 years

To all whom it may concern:

Be it known that I, ROBERT DAVOL BUDLONG, a citizen of the United States, residing at Chicago, in the county of Cook and State of Illinois, have invented a new, original, and ornamental Design for a Combined Autographic Register and Cash Drawer, of which the following is a specification, reference being had to the accompanying drawing, forming a part thereof, in which—

The figure is a perspective view of a combined autographic register and cash drawer, showing my design.

I claim:

The ornamental design for a combined auto-graphic register and cash drawer, substantially as shown.

ROBERT DAVOL BUDLONG.
